Jorgen Bettum

BY
Nector J. Evans ATTORNEY

UNITED STATES PATENT OFFICE.

JORGEN BETTUM, OF BROOKLYN, NEW YORK.

DESIGN FOR A WRITING ATTACHMENT.

52,906.

Specification for Design.

Patented Jan. 28, 1919.

Application filed April 27, 1918. Serial No. 231,263. Term of patent 3½ years.

To all whom it may concern:

Be it known that I, JORGEN BETTUM, a subject of the King of Norway, residing at Brooklyn, in the county of Kings and State of New York, have invented a new, original, and ornamental Design for Writing Attachments, of which the following is a specification, reference being had to the accompanying drawing, forming part thereof.

In the drawings:—

Fig. 2 is a side view of the same.

I claim:—

The ornamental design for a writing attachment, as shown.

JORGEN BETTUM.

Witnesses:

HUGH H. OTT,

JAMES A. KOLBE.
